LUTHER W. CAMPBELL, OF AURORA, ILLINOIS.

Letters Patent No. 63,014, dated March 19, 1867.

IMPROVEMENT IN STEAM GENERATORS.

The Schedule referred to in these Letters Patent and making part of the same.

TO ALL WHOM IT MAY CONCERN:

Be it known that I, LUTHER W. CAMPBELL, of Aurora, Kane county, State of Illinois, have invented a new and improved Generator for Superheating Steam; and I do hereby declare that the following is a full, clear, and exact description thereof, reference being had to the accompanying drawings, making a part of this specification, in which—

Figure 1 is a side view of a generator arranged within a furnace, which is shown in section.

Figure 2 is a front elevation of a furnace containing the generator.

Figure 3 is an enlarged transverse section taken through the generator at the point indicated by red line *xx* in fig. 1.

Figure 4 is a horizontal section taken through fig. 3 in the plane *yy*.

Figure 5 is a vertical section taken longitudinally through the feed-water regulator and connecting pipes.

Similar letters of reference indicate corresponding parts in the several figures.

One of the methods hitherto adopted of making superheated steam consists in subjecting water in spray directly to the action of highly heated plates, which produce an instantaneous transformation of the water, accompanied by sudden shocks and concussions. This method is not only injurious and destructive to the generators, but it is highly dangerous to life and property.

The object of my invention is to overcome the objections and the danger attending the above method of making superheated steam by arranging within a strong metallic shell or generator of a suitable size or shape, which is exposed to the direct heat of a furnace, a receiving-chamber within which the water flowing from the tank is introduced and converted into common or saturated steam, which steam then escapes into the outer chamber, where it is reheated and converted into superheated steam, thus effecting the object in view by a slower and less dangerous process than hitherto, as will be hereinafter described.

To enable others skilled in the art to understand my invention, I will describe its construction and operation.

In the accompanying drawings, A represents the furnace and covering of brick or other suitable material constructed in shape and form, in connection with the generator or series of generators, so as to obtain the proper draught and heating space. I prefer the plan and form represented, but do not confine myself to such form. B is the grate, C interior chamber of furnace, C' ash-pit, and D a superheater, which latter is made in the form of a globe, of cast iron or other suitable material. I make this superheater D thickest at the bottom, where it comes more directly in contact with the fire, to compensate as far as possible for the expansion and contraction of the metal, and to render the same as nearly equable as possible by this means. This superheater is constructed with hollow bearings on its sides, and has an elevation on top connecting with a steam dome, which latter may be, as shown, elongated so as to connect two or more generators together to increase capacity and power. The hollow bearings should have suitable heads applied steam-tight to them. The connection between the upper part of the superheater and the steam dome should also be made steam-tight by means of the flanged joint, shown in fig. 3.

E is a receiver, inside of the superheater or shell of the generator, which is made of copper or iron of any suitable thickness, and of two parts, one part inside of the other, and so far apart as to form a steam leg or steam conductor. These two parts of the receiver are confined together by stay-bolts; the inner part has a bottom, but no top, and the outer part has a top, but no bottom, which top is bolted on so that it can be removed when desired. I make the receiver by bending two sheets of metal into a tubular form, one being larger than the other, so as to leave a space for the passage of steam between them when they are put together. The inner tube has a dished bottom riveted to it, and made water-tight. The outer tube has a top bolted on and made steam-tight. The outer tube is then placed over the inner one, and the two properly secured together by stay-bolts, as stated.

This receiver E is arranged within the generator, and supported free from its bottom by means of lugs, pins, or bolts, whichever may be found most convenient.

There is also extending below, and suitably connected to the inner lining of the receiver, a cup or drip-pan for the purpose of arresting any water which may drip from the receiver, and preventing it from falling upon

the heated wall of the globe or generator; also to enable the attendant to detect any overflow, and by means of the blow-off pipe to at once eject the same. This cup is so constructed as to extend beyond the outer lining of the receiver. Below this cup is a space of sufficient size to admit under it a pipe for ejecting any water which might flow upon the generator bottom.

This receiver is constructed as described, so that the saturated steam generated therein, and rising to its top, may be conducted over the top of the inner lining down through the steam passage between the two parts of the receiver to the more heated surface at the bottom of the generator where the final superheating process takes place. The steam thus reheated rises on the outside of the receiver to the dome or upper part of the generator ready for use.

F represents a feed-water pipe connecting the water tank with the receiver. This pipe passes steam-tight through the head of the hollow bearing on one side of the generator to the receiver; and also steam-tight through both parts of this receiver E, turning upward therein, and terminating at the top thereof in the centre of an inverted cone or cup, which will divide the water discharged from said pipe into a thin sheet and cause it to fall in spray until it reaches the bottom of the receiver. F' is the inverted cone above described. G is a blow-off pipe to blow off the sediment which may collect in the bottom of the inner part of the receiver E. H is the blow-off pipe leading from the bottom of the generator. I is a similar pipe leading from the drip cup under the receiver E. K is a steam pipe for conveying steam from the dome to the engine cylinder. L common safety-valve, and M is the smoke pipe leading from the crown of the furnace.

I will now proceed to describe the feed-water regulator, which is a material part of the invention, and by which the most advantageous results can alone be attained:

I make the feed-water regulator as represented in the drawings with a loaded valve and overflow, so that at a given pressure the water may overflow and return to the tank. I also provide suitable stop-cocks between the regulator and the generator for the purpose of regulating the feed. This device enables the operator to run with a full pump, the surplus water overflowing and passing back by suitable conductors to the tank. I employ an ordinary forcing-pump, regulated by the stop-cocks and feed-water regulator, as aforesaid. F² represents the feed pipes as they connect with the stop-cocks, force-pump, (not shown,) and feed-water regulator. O passage way leading to overflow. P a loaded valve. Q overflow pipe. R valve-stem attached to the loaded lever. S is the valve-chamber, from which water flows into the pipe Q when the valve P is raised. T T are stop-cocks for gauging the feed for the supply of water to the receiver E.

I will now describe the operation, which is as follows: The proper degree of heat being obtained, the force-pump is started, and the water-feed gauged by the cocks T to the requisite quantity; the water enters the generator through the pipe F in the direction indicated by the arrows in fig. 3, and runs with a full pump, which the regulator enables the operator to do. The water is conducted by means of pipe F into the generator and conveyed to the top of the receiver where it meets the cone and cap F', and is caused to fall in a thin sheet and spray to the bottom of the receiver, or is transformed into saturated steam, the more rarefied particles of which rise through the mist and spray forced down by the inverted cone and cup to the top of the receiver, when they pass down the passage between the two parts of the receiver, and escape therefrom into the generating or superheating chamber. Here the saturated steam is reheated and conducted off for use.

When the pressure on the safety-valve is above the pressure on the water-valve, the water will stop feeding and the safety-valve will relieve itself at the pressure indicated by the external weight upon it; and when this pressure falls below the water-valve, the feed will go on as before, making the generator absolutely self-regulating.

I will further state that with a generator constructed substantially as explained, with a suitable condenser, spirits or alcohol might be used to advantage in place of water in cases of long distances where water might be difficult or impossible to obtain, as the spirits or alcohol could be used over and over until exhausted by leakage.

Having described my invention, what I claim as new, and desire to secure by Letters Patent, is—

1. The receiver for water or other liquid constructed and arranged, operating inside of a superheating steam generator which is exposed directly to the fire, substantially as and for the purpose explained.
2. A receiver E constructed so as to form two or more parts, combining an inner lining and an outer jacket, the lining having no top, and the outer jacket no bottom, with a space between them of suitable capacity to form a steam passage, substantially as described.
3. The combination of the receiver E, the cone or cap F', and the feed-water pipe F, with a superheater, substantially as described.
4. The receiver E, with the blow-off pipe G, in combination with the superheater D, substantially as described.
5. The receiver E, in combination with the cup E', and the blow-off pipe I, substantially as described.
6. In combination with the superheating steam generator constructed to operate substantially as described, I claim the feed-water regulator, operating substantially as explained.

LUTHER W. CAMPBELL.
